PRECAST FLOOR CONSTRUCTION

Henry O. Klotz, Bethel, Conn.

Application March 21, 1936, Serial No. 70,093

13 Claims.

(Cl. 72—66)

This invention relates to new and useful improvements in building construction and relates particularly to concrete building construction.

It is an object of the invention to provide a joist and floor construction of concrete or other suitable mastic material which may be precast either at the building site or elsewhere as in a shop, and then easily and quickly assembled on the job under short notice.

Another object of the invention is to provide a light weight low cost fire safe roof and floor construction.

A further object is to provide improved cementitious or molded joist construction adapted to make it possible to quickly and easily install floors and roofs.

Other objects and advantages will become apparent from a consideration of the following detailed description taken in connection with the accompanying drawings wherein satisfactory embodiments of the invention are shown. However it is to be understood that the invention is not limited to the details shown but includes all such variations and modifications as fall within the spirit of the invention and the scope of the appended claims.

In the drawings:

Fig. 1 is a perspective view with parts broken away, showing a section of a floor constructed according to the present invention;

Fig. 2 is a sectional view through the floor at a joist, the view being taken along the line of a wooden sleeper employed;

Fig. 3 is a perspective view on a smaller scale showing a portion of a joist prior to its assembly in a roof or floor;

Fig. 4 is a similar view showing a reenforced precast cementitious slab employed;

Fig. 5 is a view partly in section and partly in elevation showing a portion of a joist and the manner in which wooden sleepers are secured in place;

Fig. 6 shows a slightly modified arrangement wherein the entire floor is of concrete or mastic material, the wooden sleepers being omitted and flat iron tie bars being substituted for the sleepers;

Fig. 7 is a detail perspective view taken at right angles to Fig. 6 and showing more particularly the manner in which the flat iron tie bars are secured in place;

Fig. 8 is a perspective view showing a carrying girder made up according to the present invention and supporting the ends of joists;

Fig. 9 is a detail sectional view showing the use of a saddle in the formation of a girder;

Fig. 10 is a sectional view taken substantially along the plane indicated by the line 10—10 in Fig. 8;

Fig. 11 is a view similar to Fig. 8 but showing another construction and arrangement of girder and joist; and

Fig. 12 is a sectional view taken substantially along the plane indicated by the line 12—12 in Fig. 11.

Referring to the drawings the invention is shown as applied to the formation of a floor although it is to be understood that it may be used in constructing the roof of a building. According to the invention precast cementitious or mastic joists and slabs are to be cast or formed either at the building site or at a shop or the like remote from the scene of the actual erection of a building so that when they reach the building operation they are thoroughly set and cured and there is no making of forms or the like at the point of erection of the building and no waiting during the building operation for the various parts to set and cure. Therefore the building may be rapidly erected.

In the first form of the invention, that is Figs. 1 through 5 the floor comprises precast cementitious material such as concrete joists 10 each including a body of the desired length having horizontal shoulders 11 at its opposite sides intermediate its height. The lower portion of each joist is thus thicker than the upper portion thereof and in the lower portion is a reinforcing metal tension bar 12 while in the upper portion of the joist there is a metal compression bar 13.

Stirrups 14 extend between and connect the bars 12 and 13 at spaced points, and while these stirrups are ordinarily spaced four to six inches apart the spacing depends on the load to be carried. Each stirrup 14 comprises a bar or length of metal having its upper portion bent to provide a hook 15 partially embracing the reinforcing bar 13 and having its lower portion bent partially about the reinforcing bar 12 and extending at the lower side of the same toward a side of the body of the joist.

The stirrups are arranged with the lower horizontally disposed portions 16 of adjacent stirrups extending in opposite directions. With this arrangement the said portions of the stirrups assist in locating the metal reinforcing means in the mold prior to the pouring of the cementitious portion of the joist and retain it properly centered during the pouring operation, and such

stirrup portions also reenforce the side shoulders of the joist. By spot welding as at 17, or in any other suitable manner, the stirrups 14 are secured or tied to the bars 12 and 13.

5 In their upper edges at suitably spaced locations the joists are provided with notches 18 designed to accommodate wooden sleepers 19 adapted to have wooden flooring 20 nailed or otherwise secured thereto. At locations spaced 10 apart as are the notches or recesses 18 cotter pin or hair pin stirrups 21 are embedded in the body of the joist and such stirrups straddle the bars 12 and 13 (see Fig. 2) and are spot welded to them as at 22, and the free end portions 23 and 15 24 of the stirrup arms extend up through the notches 18. It is particularly noted (see Figs. 3 and 5) that one stirrup end portion or arm as for example 23 is somewhat longer than the end 24. The purpose of this arrangement will later 20 be set forth.

The wooden sleepers 19 project slightly above the upper edges of the joists, in the neighborhood of a quarter of an inch, and at points spaced apart along their lengths the sleepers are 25 provided with holes 25 to receive the projecting ends of the arms of the hairpin-like stirrups 21. Joists 18 are spaced according to the load to be carried and the holes 25 in the sleepers are spaced to agree with the spacing of the joists. 30 Therefore the parts check on one another and the sleepers are easily located. They also properly locate the joists and prevent their being accidentally shifted as the floor slabs 26 are mounted in place. The ends 23 and 24 of the 35 stirrups are of such length as to extend entirely through the sleepers and after the sleepers are in place the said ends are bent over as shown best in Fig. 1 and the left hand portion of the Figure 5. Since the ends are of different lengths 40 the longer may be struck as with a hammer to bend it over and when the longer is out of the way the other may be bent over in like manner. This saves time and facilitates the bending over operation as it is not necessary to separate the 45 stirrup ends with a tool before bending them over. Also the bent ends of the stirrup arms serve to secure the sleepers in place.

Filling the space between each pair of the joists are precast cementitious slabs 26. They 50 may be of concrete or other mastic material. From Fig. 4 it will be noted that these slabs may be reenforced with metal bars 27 extending longitudinally and transversely thereof and preferably each slab carries a tongue 28 at one end 55 and a corresponding groove 29 at its other end. The slabs 26 are of such width as to have their side edge portions rest on the side shoulders 11 of the joists when the slabs are in place.

Such side edge portions of the slabs are shown 60 as slightly tapered so that the slabs are not as wide at their upper as at their lower edges. This leaves wedge shaped recesses 30 between the edges of the slabs and the upper vertical portions of the joists. When the slabs are in place 65 electrical conduits, pipes, or the like may be placed on the slabs and extending below the sleepers. Thereafter grouting 31 may be poured filling the spaces 30 and over the slabs 26 sealing such slabs in place. Also this grouting flows 70 through holes or openings 32 in the web portions of the joists forming dowels whereby the entire structure is interlocked.

Thereafter the floor may be poured with concrete or the like 33 filling the space (see Fig. 1 75 left hand side) between the joists and if desired

covering the joists and coming up flush with the upper edges of the sleepers. It is desirable that the slabs 26 as well as the grouting 31 and the fill 33 be of cinder concrete or other light aggregate. After the fill is in place the wooden flooring 20 may be nailed or otherwise secured to the sleepers 19. It will be appreciated that in the manner and with the parts specified a floor may be quickly erected and that in the finished product a substantial and integral structure is 10 provided. The grouting and the fill serve to bind all parts in place. Of course the slabs are assembled with the tongue of one in the groove of the next. The sleepers are held against any upward movement by the bent ends of the hairpin stirrups 21.

Referring now to the modification shown in Figs. 6 and 7 a floor having a cementitious top surface is shown. In building this type of floor after the slabs 26 are in place, instead of the 20 wooden sleepers 19 flat iron tie bars 34 are disposed extending through the notches 18 in the joists and the extending arms 23 and 24 of the stirrups 21 pass through holes in these tie bars and are bent over to secure the tie bars in place. 25 Thereafter fill 35 is poured and it encloses the tie bars and fills the notches 18. A finishing or surface layer 36 of cement, terrazzo, marble or any composition flooring then completes the job. If desired the ends of the tie bars may be turned 30 up as at 37 to insure a lock between said bars and the surrounding concrete.

Referring to the modification of Figs. 8, 9 and 10 a floor including a carrying girder 38 is shown. Such girder is made up of a pair of the precast 35 joists 10a arranged in parallel relation and spaced a slight distance apart. Saddles 39 (see Fig. 9) are arranged with their lateral arms 40 in the dowel openings 32 of said joists and with their V-shaped body portions between such joists and 40 such saddles support a reenforcement comprising a lower rod 41 and an upper rod 42 which are connected through stirrups 14a. The stirrups 14a are spot welded or otherwise secured to the bars 41 and 42 to form them into a unit which 45 is supported between the two joists 10a by the saddles 39.

At the other sides of the joists 10a and running at right angles to them are joists 10b of substantially the same construction as the joists 50 10 of Fig. 1 and including the reenforcing bars 12 and 13 together with the stirrups 14 and 21 the latter serving to tie the wooden sleepers 19 in place as will be understood. Hook-like tie members 43 have portions spot welded to the bars 13 of the joists 10b as at 44 and include portions 45 projecting beyond the ends of the joists. The ends of the joists at the girder are undercut as at 46 so that the ends of the joists 10b rest on the shoulders at the outer sides of 60 the joists 10a of the girder 38. This is shown in Fig. 8 and there it is noted the tie rod hook portions extend through the notches 18 in the upper edges of the joists 10a so as to be disposed or enter into the space between such joists. 65

When the parts have been assembled as specified a cementitious material, such for example as concrete, is poured into the space between the joists 10a thus forming in effect a third joist 47 the position of which is reversed with respect to 70 the joists 10a. Thus it will be seen that the girder 38 is made of three joists of which the outer two are precast while the intermediate one is cast in the field, and they are all connected forming a unitary girder. The mastic material 75

5 poured to form the intermediate joist of the girder encloses the reenforcing bars 41 and 42 and the stirrups 44a and also the saddles 39 and the projecting portions 45 of the tie members 43. Additionally the material of the intermediate member 47 of the girder flows into the dowel openings 32 of the joists 10a forming what might be termed dowel pins 48, and such material also fills the notches 18 in the upper edges of the joists 10 and fills the spaces between and over the joists 10b as at 49 whereby all the parts are securely bound together. It will be seen this arrangement makes a flush ceiling.

10 In the modification shown in Figs. 11 and 12 15 a flooring the same as that shown in Fig. 1 and including joists 10 is supported at the upper side of a girder 50 portions of which are precast and a portion of which is cast in the field. A comparison of Figs. 8 and 11 will show that while the 20 joists are on top of the girder in Fig. 11 they are at the sides of the girder in Fig. 8 so that in the latter figure the bottoms of the joists are flush with the bottom of the girder.

25 The girder 50 comprises similar outer members in the form of precast L-shaped joists 51 and 52 arranged with their toe portions extending toward one another and each including upper and lower reenforcing bars 53 and 54 connected by stirrups 55 to which they are spot welded at 56. The lower portions 57 of the stirrups are arranged horizontally extending toward one another so as to reenforce the toe portions of the L-shaped joists.

30 The joists 51 and 52 are spaced apart a distance 35 depending on the girder to be formed, and arranged between such joists are upper and lower reenforcing bars 58 and 59 connected at suitably spaced points by stirrups 60 spot welded or otherwise secured to them. Iron rod ties 61 extend 40 horizontally from the joists 51 and 52 into the space between such joists and into any desired relation to the bars 58 and 59 and stirrups 60. Their ends are preferably turned laterally or curved as shown at 61a to anchor them in the 45 beams 51 and 52, they being cast therein when the beams are cast. With these reenforcing members in place a cementitious material such for example as concrete is poured into the space between the joists 51 and 52 and the joists, and 50 such material together with the various reenforcing elements make up the girder 50 which in effect is a unitary structure comprising the outer precast joists 51 and 52 and the inner precast joist-like part 62 which is cast in the field.

55 It is to be understood that the floor construction of the joists 10 and 10b, may be used with steel girders in place of the girders 38 and 50.

From the foregoing it will be seen that the slabs 60 26 may be very easily installed since they require no cement bed and are interlocking. They may be reenforced with rods as shown or with expanded metal or other reenforcing fabric as desired. While the tension and compression bars and stirrups have been shown and described as 65 connected by spot welding it will be understood that they may be clipped or tied together with wire or connected in any other suitable manner. The joists may be used without the precast slabs 70 in which case ribbed metal lath or other self centering material resting on the shoulders of the joists would be used and the entire floor between the joists would be poured during erection of the building. Material other than concrete may be used in making any of the various 75

parts, and the undersides of the joists and slabs are preferably kept smooth to present a neat and finished appearance which can be painted, white washed or the like. Metal lath to receive plaster may be applied to the undersides of the joists 5 by means of wires whereby to form a flat ceiling.

Having thus set forth the nature of my invention, what I claim is:

1. A cementitious joist comprising a body having side shoulders intermediate its height, upper 10 and lower reenforcing bars in and extending longitudinally of said body, upright stirrups at spaced intervals in said body and connecting said bars and having their lower end portions extending toward the sides of the body, and said 15 stirrups arranged with the lower end portions of adjacent stirrups extending in opposite directions whereby said portions assist in locating the stirrups in the mould prior to pouring of the joist and in the complete joist extend under and 20 strengthen the shoulder portions thereof.

2. A joist comprising a cementitious body having a plurality of spaced transverse notches in its upper edge to receive wooden sleepers or tie bars, 25 tension and compression reenforcing bars in the body, hairpin-like stirrups in the body and connected with said bars and having the free end portions of their arms extending into said notches to secure the sleepers or tie bars.

3. A roof or floor construction comprising 30 spaced supporting joists having side shoulders intermediate their height, stirrups in said joists and extending at the upper sides thereof, wooden sleepers extending across said joists and having spaced holes receiving the extending stirrup portions whereby to locate the sleepers and joists relatively, and cementitious means filling the 35 space between said joists.

4. A roof or floor construction comprising 40 spaced supporting joists having side shoulders intermediate their height, stirrups in said joists and extending at the upper sides thereof, wooden sleepers extending across said joists and having spaced holes receiving the extending stirrup portions whereby to locate the sleepers and joists relatively, precast cementitious slabs between 45 each pair of said joists and having their edge portions resting on the side shoulders of the joists, and grouting sealing said slabs in place.

5. A roof or floor construction comprising 50 spaced supporting joists having side shoulders intermediate their height, stirrups in said joists and extending at the upper sides thereof, wooden sleepers extending across said joists and having 55 spaced holes receiving the extending stirrup portions whereby to locate the sleepers and joists relatively, precast cementitious slabs between each pair of said joists and having their edge portions resting on the side shoulders of the joists, and the slabs between a pair of said joists having interlocking connections with one another.

6. A cementitious joist comprising a body having 60 a plurality of spaced transverse notches in its upper edge to receive wooden sleepers or tie bars, tension and compression reenforcing bars in the body, hairpin-like stirrups in the body and connected with said bars and having the free end portions of their arms extending into said 65 notches to secure the sleepers or tie bars, and one of the arms of said stirrups being longer than the other whereby the arms may be bent in opposite directions by striking them with a hammer or the like.

7. A precast joist comprising an elongated cementitious body, a compression reenforcing bar for the joist in the upper portion thereof and a tension reenforcing bar in the lower portion, a transverse wooden sleeper at the top of the joist, and a hairpin-like stirrup in the body connecting said bars and having the free end portions of its arms extending at the upper side of said body and through the sleeper for the purpose of securing the sleeper to the joist.
8. A precast joist comprising an elongated cementitious body, vertically spaced compression and tension reenforcing bars in said joist, a hairpin-like stirrup in the body connecting said bars and having the free end portions of its arms extending at the upper side of said body, said free ends being adapted to be passed through a transversely extending wooden sleeper or tie rod and bent to secure the sleeper or tie rod to the body, and one of the arms of said stirrup being longer than the other whereby the arms may be bent in opposite direction by striking first the longer and then the other arm.
9. A roof or floor construction comprising spaced supporting joists having side shoulders intermediate their height, precast cementitious slabs between each pair of joists and having their edge portions resting on the side shoulders of the joists, said joists having spaced transverse openings therethrough above said shoulders, and grouting sealing said slabs in place and interlocking the slabs at one side of a joist with those at the other side thereof by flowing into and filling said openings.
10. A roof or floor construction comprising spaced supporting joists having side shoulders intermediate their height, stirrups in said joists and extending at the upper side thereof in the form of a pair of arms, flat iron tie bars extending across said joist and having holes through

which said stirrups pass, said stirrups having their projecting portions bent over and securing the tie bars in place, and cementitious material filling the spaces between said joists and enclosing said tie bars.

11. A roof or floor construction comprising a girder including a pair of precast cementitious joists each having side shoulders intermediate its height, floor joists at the sides of said girder and having their ends resting on the outer side shoulders of the girder joists, tie bars extending from said floor joists into the space between the girder joists, iron reenforcing bars in said space and extending longitudinally thereof, and a cementitious filler in said space and enclosing said tie and reenforcing bars and securing all the parts together.

12. A roof or floor construction comprising a girder including a pair of precast cementitious joists each having side shoulders intermediate its height, floor joists at the sides of said girder and having their ends resting on the outer shoulders of the girder joists, tie bars extending from said floor joists into the space between the girder joists, and a cementitious filler in said space and enclosing said tie bars and securing all the parts together.

13. A precast joist comprising an elongated cementitious body, a compression reenforcing bar for the joist in the upper portion thereof and a transversely extending tie bar resting on the joist at the top thereof and projecting laterally therefrom, a hairpin-like stirrup in the body connecting said reenforcing bars and having the free end portions of its arms extending at the upper side of said body and bent over the tie bar for the purpose of securing the tie bar to the joist.

HENRY O. KLOTZ.
